UNITED STATES PATENT OFFICE

106,557

DESIGN FOR A DRESS ENSEMBLE

Mabel Arkin, New York, N. Y.

Application September 13, 1937, Serial No. 71,598

Term of patent 3½ years

To all whom it may concern:

Be it known that I, Mabel Arkin, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear coat portion of the dress ensemble is conventional.

I claim:

The ornamental design for a dress ensemble, substantially as shown, and described.

MABEL ARKIN.
